(57) **CLAIM**

The ornamental design for a neck and shoulder heating pad and massager, as shown and described.

DESCRIPTION

FIG. 1 is a top plan view of a neck and shoulder heating pad massager showing my new design;

FIG. 2 is a side elevational view thereof; and,

FIG. 3 is a side perspective view thereof, in use.

All sides not shown in the drawing disclosure forms no part of the claimed design.

The broken line showing of a human figure, a remote control box and cord illustrates environmental structure and forms no part of the claimed design.

The dashed lines shown directly on the surface of the claimed article, throughout the views, are understood to represent stitching, and form part of the claimed design.
